COAT

Otto F. Weisend, Columbus, Ohio

Application January 4, 1934, Serial No. 705,247

3 Claims. (Cl. 2—93)

This invention relates more particularly to coats for men and has for its principal object to provide a construction of coat that conforms more nearly than heretofore to the figure of the wearer at the back and posterior. One result of the construction is that the upper back is, in normal use, maintained in a smooth and unrumpled condition. Other objects will appear from the disclosure herein.

10 The invention is embodied in the example herein shown and described, the features of novelty being finally claimed.

In the accompanying drawing—

15 Figure 1 is a view in rear elevation of a coat containing the invention.

Fig. 2 is a view in elevation looking at the left hand side of the coat.

20 Fig. 3 is a view on a larger scale of a fraction of the coat looking at the inner side of the rear 20 and illustrating details of construction at the junction of the tail with the top of the back.

Fig. 4 is a vertical section on a larger scale, on say the line IV—IV Fig. 3.

25 Fig. 5 is a horizontal section on the line V—V Fig. 3 but on a larger scale.

Fig. 6 is a plan view of the piece to form the belt used in the construction.

In the views 10 designates the upper portion of the coat. 11 designates the tail portion of the 30 coat. Said upper portion and tail can each be made of one or more pieces. The lower edge of the upper portion of the back is cut on a curve convexed upward and on the bias and the upper edge of the tail portion is cut similarly, substan-

35 tially as indicated, so that the margins of said portions can be lapped—one upon the other—and the two basted together parallel to said curves and subsequently sewed with a stay piece or tape 12 of flexible material preferably by a

40 line of stitching 13. The stay piece 12 is first sewed to the upper portion of the back from side seam to side seam and before the application of the lower tail part and said stay prevents the bias edge of the upper part of the coat from 45 stretching and holds the entire edge of the back

firmly to permit the fulling in the skirt to produce the rounding effect shown. The pleats

18—18 are made before the stay piece 12 is sewed on the upper portion of the inner side of the 50 coat, but in fastening said tail portion and the back, as stated, the upper edge of the tail portion is first pleated at 14, 14, and gathered so as to produce a fullness or bulging near the top of the tail portion and therefore to fit more or less

55 snugly, as best indicated in Fig. 2, over and

around the rumps or posterior of the wearer. Provision is made for securing this bulging or fullness effect at the upper portion of the tail by primarily cutting the tail portion of sufficiently greater width at the top to allow the desired pleating or gathering preparatory to stitching the tape and the tail and upper portion of the back together. To conceal the connection between the tail portion and top portion of the back at the exterior of the coat there is provided a belt, so called, or strip 15 made preferably of the same fabric as that of which the coat is made and of approximately the length of the distance between the side seams of the coat. Said belt is formed by folding inward the opposite longitudinal margins of the strip 15 as indicated in Figs. 3 and 4. This folded strip or belt is first sewed along its upper margin by a line of stitching 16 to the upper portion of the back on a line substantially paralleling the stitching of the tape 12 thereby producing a flare of the lower margin of the belt and subsequently stitching said lower margin of the belt to the upper portion of the tail as indicated by the line of stitching 17.

The belt or strip 15 is primarily and preferably made of a straight piece or pieces, such as shown in Fig. 6, so that when curved and applied as described it forms an arch, there being a slight stretching along the upper margin, and a flaring of the material along the lower edge thereof, 85 this aiding in producing and maintaining the fullness or bulging effect at the upper portion of the tail of the coat.

The upper portion of the back of the coat can be made with or without pleats such as shown 90 at 18 and 18, the pleats 14, 14, in the tail being made to appear as continuations of such pleats. Also the tail portion can be made with or without a box pleat, such as shown at 19, in the middle of the tail of the coat. The coat can be lined 95 and otherwise made as usual or as required by the customer.

The forms of the parts can be changed without departing from the gist of the invention as claimed.

100 What I claim is:

1. A coat including an upper back portion having its lower edge cut on an upwardly convexed line and provided with a binder adjacent said line, and a distinct tail portion having its upper portion cut on an upwardly convexed line and gathered to produce a fullness and secured in gathered condition to said lower edge of the upper back portion.

2. A coat including an upper back portion hav-

ing its lower edge cut on an upwardly convexed line and provided with a binder adjacent said line, a distinct tail portion having its upper portion cut on an upwardly convexed line and gathered 5 to produce a fullness and secured in gathered condition to said lower edge of the upper back portion, and an arched belt secured to the exterior of said united upper and tail portions and covering the junction between them.

10

3. A coat including an upper back portion having secured thereto on its lower margin an upwardly convexed binder, a distinct tail portion having its upper margin gathered to produce a fullness and secured in such gathered condition to the lower margin of said back portion on a line substantially coinciding with the said upwardly convexed binder on the back portion.
